[57] ABSTRACT

Puffed oats are used alone or with tobacco to provide smoking materials.

11 Claims, No Drawings

SMOKING MATERIALS

This invention relates to novel smoking compositions and to products derived therefrom.

It is a principal object of this invention to provide a composition of matter which is advantageous for use as a smoking material.

It is another object of this invention to provide novel compositions containing tobacco which compositions can be used to form products such as cigarettes, cigars, pipe tobacco and the like.

The present invention involves the discovery that oats which are in an expanded condition and of relatively low density are eminently suitable for use as a smoking material.

In one embodiment, the invention provides smokable compositions comprising a mixture of tobacco and puffed oats. The puffed oats serve as a tobacco extender without significant effect on the organoleptic properties of tobacco products in which they are present. In a second embodiment of the invention, puffed oats are used alone or with other non-tobacco materials to form smoking materials.

The oats which are utilized as a smoking material in accordance with this invention are oats which have been processed to expand their volume and decrease their density whereby they are in an expanded condition supportive of combustion. Various oat species can be used including, for example, *Avena sativa* and *Avena byzantina*. Processing of the oats to expand their volume involves puffing so as to produce puffed oats of relatively low density. In general, the bulk density of the puffed oats employed herein is not greater than about 0.40 gram per cubic centimeter and preferably not greater than about 0.20 gram per cubic centimeter. The expression "puffed oats" as used herein means oats which have been expanded to such extent that the bulk density is not greater than 0.40 gram per cubic centimeter when determined on a 12-mesh sample. For this determination of bulk density the oats are ground in a suitable mill and sieved to recover the 12-mesh (U.S. Sieve Series) portion thereof with a uniformly packed sample of known volume then being weighed.

The volume expansion of oats can be accomplished by puffing procedures well known to the art. As is known, puffing of oats is accomplished by gun puffing which is the release of cereal pieces from a pressurized chamber or oven puffing where the cereal dough pieces are exposed suddenly to high temperatures. The oven method may involve exposure to radiant heat on a belt, tumbling in a heated rotating cylinder, exposure to heated rolls, or extrusion at high pressure and elevated temperature. Puffing of oats and other similar materials is a well developed art and there exist a number of patents relating to puffing processes and apparatus. Puffing of oats for use in accordance with this invention can be accomplished using known procedures and apparatus such as described in U.S. Pat. Nos. 3,456,575, 2,701,200, 2,231,387, 3,656,965, 3,703,379, 3,556,802, 3,392,660, 3,201,032, 3,660,110 and 3,682,651. After puffing, the puffed oats are separated from non-puffed kernels by conventional procedures such as screening, air classification and the like. The size and shape of the puffed oats which are used to form smoking materials is primarily dependent upon intended use. It is generally preferred to grind, or more preferably shred, or otherwise comminute, the puffed

5 oats to a size and shape approximating that of the tobacco with which they are employed. Thus, when employed with tobacco to form cigarettes, the puffed oats are cut, sliced or shredded to a size and shape similar to the filler tobacco employed therewith. It is preferred to do likewise when the puffed oats are used with tobacco to form cigars or pipe smoking compositions.

10 When used with tobacco, puffed oats are blended with tobacco and the blend is then processed in conventional manner to form tobacco products. For example, puffed oats are shredded to a size approximating that of cut filler tobacco with which they are blended in desired proportion. The blend is then processed in conventional cigarette making machines to form cigarettes which can be either of the filter or nonfilter type. Additive materials such as flavorants, humectants, ash improvers, combustion modifiers, fillers and the like can be incorporated with the tobacco/puffed oats blends. Pipe or smoking tobacco products can be readily produced by simply blending the puffed oats with tobacco and flavorants, if any.

15 It will be appreciated that the use of puffed oats with tobacco serves to extend the tobacco or reduce the amount of tobacco employed in a product with a concomitant decrease in the amount of nicotine therein. This is achieved without adverse effect on the taste or aroma of the final product. The amount of the puffed oats blended with tobacco can vary widely up to about 50 percent or more by volume of the tobacco.

20 According to a second embodiment of the invention, puffed oats are employed as a tobacco substitute by themselves or with other non-tobacco materials to form smoking products such as cigarettes, cigars and pipe smoking products. When so used, it is presently preferred that the puffed oats simulate tobacco and accordingly appropriate procedures can be employed to provide the puffed oats in desired size and shape. The burning rate, flavor and other properties of non-tobacco smoking products can be altered by incorporating with the puffed oats suitable additives such as flavorants, tobacco extracts, nicotine, humectants, ash improving additives, etc. The burning rate of puffed oats is somewhat faster than most natural tobaccos and accordingly, to decrease the burning rate of non-tobacco smoking products, suitable filler materials or combustion modifiers such as magnesium carbonate, calcium carbonate, potassium carbonate, sodium carbonate, magnesium nitrate, calcium nitrate and the like can be incorporated with the puffed oats. The materials 25 which are used with the puffed oats to form smoking products are employed in amounts depending upon the effects desired.

30 When used with or without tobacco to form smoking materials, the puffed oats are preferably conditioned to a moisture content of say from 6 to 15 percent at which moisture content the material is well adapted for processing to form smoking products.

35 The following examples illustrate the advantages of the present invention. In the examples the bulk density of the tobacco extender of this invention was determined by weighing a known volume of the puffed oats as indicated. However, in all cases the bulk density of the materials is less than 0.40 gram per cubic centimeter when determined on a 12-mesh sample thereof.

EXAMPLE 1

40 Bulk density measurements were made on puffed oats which had been previously stored at 60 percent

relative humidity until an equilibrium moisture content of about 6.5 percent was reached. The puffed oats were then ground in a Waring blender and sieved. Various particle sizes were collected and the bulk densities thereof were determined by weighing a 50 cubic centimeter volume of uniformly packed material. The packing was accomplished by rapping the bottom of the container frequently during the packing operation so that the particles settled evenly. No external pressure was applied to the mass of particles in making this measurement. The densities of the materials retained on various mesh screens are shown in Table I. For comparison purposes, the densities of selected tobacco materials are shown in Table II.

found to be 26.5 milliliters per 3-gram sample at a moisture content of 7.52 percent.

EXAMPLE 3

- 5 Cigarettes were prepared from shredded puffed oats by blending either 20 or 50 percent by volume of the shredded oats with 80 or 50 percent by volume of a commercial cigarette tobacco. The tobacco-puffed oats blend was then manufactured into cigarettes using 10 Ecusta Ref. 853 paper. The resulting 65-millimeter tobacco rods were combined with 20 millimeters of a 3.3/39,000 cellulose acetate filter and the finished filter cigarettes were smoked under standard FTC conditions to give the following results:

Rod Composition (Rod length: 65 mm)	Rod Weight in grams	TPM* (mg.)	Nicotine (mg.)	FTC** Tar (mg.)
All Tobacco	0.89	25.1	1.33	18.9
20% (vol.) Puffed Oats 80% (vol.) Tobacco	0.80	23.9	1.17	18.5
50% (vol.) Puffed Oats 50% (vol.) Tobacco	0.65	24.8	0.98	19.0

*Total Particulate Matter

Commercial cigarette blend without casing or top dressing	0.11 g/cc

*Puffed in accordance with U.S. patent No. 3,524,451

EXAMPLE 2

The filling capacity of puffed oats was determined. The shredded puffed oats were cut in 32 shreds per inch and were very much like tobacco shreds.

In order to measure the filling capacity of a cigarette filler material, a measuring device is used which is essentially composed of a 100 milliliter graduated cylinder having an internal diameter of about 25 millimeters and a piston having a diameter of about 24 millimeters and weighing about 802.5 grams slidably positioned in the cylinder. A 3-gram sample of the material is placed in the cylinder and the piston positioned on it. The gravitational force exerted by the piston corresponds to a pressure of about 2.3 pounds per square inch. The filling value of the sample is the volume to which the 3-gram sample of the material in the cylinder is compressed after the weight of the piston has acted on it for a period of 3 minutes. This pressure corresponds closely to the pressure normally applied by the wrapping paper to the tobacco in cigarettes. By this procedure the filling capacity of the puffed oats was

30 Cigarettes containing 20 percent by volume of the shredded puffed oats were smoked by expert panelists in comparison with an all tobacco control cigarette. Although a majority of the panelists regarded the all tobacco cigarette as having better over-all flavor, the oats-containing cigarettes were adjudged to be milder 35 by 40 percent of the panelists while 25 percent detected no difference in mildness. Thirty-five percent of the panelists indicated either a preference for the test cigarette or no difference between the test and control as to which was preferred.

40 The use of puffed oats with tobacco to produce useful products possesses numerous advantages. Thus, use thereof permits a significant reduction in the utilization of tobacco. Not only is the use of less tobacco in a tobacco product obviously advantageous from an economic standpoint, but the reduction of nicotine in such products may be highly desirable. The nicotine-free puffed oats, when blended with tobacco, do not cause adverse effects on the quality of the final product. The puffed oats are easily processed, readily available at

50 relatively low cost and do not detract from the taste or aroma of the tobacco product. The puffed oats are non-friable in nature, do not collapse as a cigarette is smoked nor do they hinder combustion or puffing of cigarettes in which they are employed.

55 Those modifications and equivalents which fall within the spirit of the invention are to be considered a part thereof.

What is claimed is:

1. A smoking material which contains comminuted puffed oats in a form resembling cut cigarette filler tobacco or cut pipe tobacco.
2. A smoking material in accordance with claim 1 wherein the puffed oats are in the form of shreds.
3. A smoking material in accordance with claim 1 which also contains tobacco.
4. A smoking material in accordance with claim 3 wherein the puffed oats are employed in an amount up to 50 percent by volume of the tobacco.

5. A cigarette whose filler contains comminuted puffed oats in a form resembling cut cigarette filler tobacco.

6. A cigarette in accordance with claim 5 wherein the puffed oats are in the form of shreds.

7. A cigarette in accordance with claim 5 whose filler also contains tobacco.

8. A cigarette in accordance with claim 7 wherein the puffed oats are employed in an amount up to 50 percent by volume of the tobacco.

9. A process of preparing a cigarette which comprises wrapping with a cigarette paper a filler material containing comminuted puffed oats in a form resembling cut cigarette filler tobacco.

10. A process in accordance with claim 9 wherein the puffed oats are in the form of shreds.

11. A process in accordance with claim 9 wherein said filler material also contains tobacco.
